UNITED STATES PATENT OFFICE.

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS.

SCRAPER.

Application filed February 29, 1924, Serial No. 695,894. Renewed June 23, 1926.

This invention relates to improvements in turning devices for scrapers adapted for reciprocable movement in gathering loose material and has for its principal object to 5 provide an improved construction of apparatus of the class described.

My invention is particularly adapted for use in mines where the course of movement of the scraper is restricted along certain 10 paths, as for instance in the room and pillar system of mining coal in which the coal is gathered by moving the scraper along the working face at one end of the room but must be turned at an angle at the corner of 15 the room for movement along a cleared path at one side of the room to the entrance thereof for loading into mine cars. One of the main problems in the operation of a scraper device under these conditions has 20 been to devise facile and efficient means for controlling the movement of the scraper and its draft lines so as to change its course without the use of cumbersome apparatus or excessive labor.

25 In the present invention I provide an improved apparatus whereby a draft line guide is fixed under tension at the desired point of turning, with the draft line deflected thereabout, but by means of a by-passing element extending about one side of the scraper and continuous with the draft ropes at opposite ends thereof, the rope guide is permitted to pass about the scraper either in a forward or rearward direction and the 30 scraper is thus turned in its course without danger of tipping.

The invention may be best understood by reference to the drawings which illustrate one form in which it may be embodied.

40 In these drawings:

Figure 1 is a plan view of a scraper constructed in accordance with my invention, with parts broken away.

Figure 2 is a front end view of the scraper 45 shown in Figure 1.

Figure 3 is a view showing the holding jack and guide in cooperating engagement with the scraper, the latter being shown in section on line 3—3 of Figure 1.

50 Figure 4 shows a modified form of guide holding bracket.

Figures 5, 6 and 7 are diagrams illustrating the operation of the scraper as applied to a coal mine using the room and pillar 55 system of mining.

Referring now to the details, the drawings show a scraper 1, preferably of the bottomless type, having side walls 3 and 2 converging toward the rear, as shown. Two draft ropes for moving the scraper reciprocably comprise a head line 4 and a tail line 5. Said head rope and tail rope are attached at the forward and rearward ends respectively of a by-pass guiding member 6. This by-pass member is carried in a substantially horizontal plane about one side of the scraper so as to afford an inwardly facing bearing surface or track 7 substantially continuous with the head rope and tail rope 4 and 5. Said ropes are each connected to 70 said track at a point substantially on the longitudinal axis or bisecting line of the scraper so as to exert a normal pull thereon in a longitudinal direction.

A reinforcing strip 8 may be secured on 75 the track 7, extending from a point adjacent the front end of the scraper to the rear end of said track. As shown herein the by-pass member intersects the side wall 2 adjacent the forward end and passes 80 around the rear end of the scraper. Suitable means of rigidly securing said member to the scraper are provided as herein shown comprising rear brackets 9, 9, connected to the reinforcing strip 8 above the track 7, and an 85 elongated laterally extending bracket 10 on the side wall 2 of the scraper and similarly attached to the reinforcing strip 8 as shown in Figure 3.

The securing brackets 9, 9 and 10 are arranged above the by-pass member 7, and an elongated slot 11 is formed horizontally about the side wall 2 beneath said member to permit free passage of a holding sheave around the scraper, as will now be described. 95

Referring to Figure 3 and the diagrams shown in Figures 5, 6 and 7, it will be seen that the object of the by-pass member is to provide a continuous bearing with both draft ropes 4 and 5 for a guide sheave 12 secured at the point where it is desired to change the course of movement of the scraper, as for instance, in a corner of a mine room 13. This guide sheave is secured by suitable means at the proper height to 105 engage the by-pass track 7. As herein shown this means comprises a bracket 14 having an upper arm 15 carrying said sheave and curving downwardly and back upon itself to form a foot 16 adapted to engage the ground. 110

The bracket is secured in place by a mine jack 17 of the usual form. As shown herein the mine jack is inclined slightly toward the sheave, this usually being the preferred 5 position for securing a jack in place, although it will be understood that the jack may be arranged at varying angles, or vertically, as desired. The jack extends through a longitudinal slot 18 longitudinally in the 10 upper arm 15 and a loose fitting hole 19 in the foot member 16. By reason of the loose connection of the bracket to the jack, the arm 15 and its sheave is free to rock in a vertical plane and thus accommodate variations 15 in the vertical height of the scraper. The bracket also has limited pivotal movement on the jack. In Figure 4 a modified form of holding bracket is shown in which the arm 15^a is pivoted at 29 to permit vertical movement of said arm with respect to 20 the holding jack. In this instance also limited rotation of the bracket is afforded.

In order to maintain the forward end of the slot 11 clear of loose material for the 25 rearward movement of the guide sheave about the by-pass member 6, an inwardly extending shield 20 is secured to the upper and lower margins of said slot. As shown herein this shield is attached to a pair of inwardly extending flanged members 21 and 22, attached to the side wall 2. This shield also provides reinforcement to the scraper which is opened along one side at this point, as described.

35 The head and tail ropes 4 and 5 are preferably engaged by grooved end portions 23 and 24 at the forward and rearward ends respectively of the by-pass member 6, so as to provide the desired continuous bearing 40 surface for the guide sheave 12. The ends of the ropes are secured to said guide member by suitable means such as eyes 4^a, 5^a, respectively extending into slots 25 and 26 and secured by pins 27 and 28, passed through 45 their respective eyes.

The use and operation of the device above described is as follows:

Referring to the diagrams in Figures 5, 6 and 7, the scraper is shown in three positions in the mine room 13. In Figure 5 the scraper is gathering a load of loose material adjacent the working face 30, said scraper being moved forwardly by means of the head rope 4 which is passed at an angle 50 about the guide sheave 12 secured by a bracket 14 in the corner of the room adjacent the side wall 31 of the room. In this instance the tail rope 5 extends over a guide sheave 32 fixed in a suitable position in the 55 far corner of the room and from thence to a suitable winding drum (not shown) which may be in any desirable position to control the operation of the head and tail ropes in the usual manner.

60 As the scraper is moved forwardly under

the tension of the head rope it reaches a position in which the guide sheave 12 engages the inner surface of the by-pass member 6, this surface being continuous with said head and tail ropes, as heretofore described. The scraper is deflected and a turning movement is produced while the guide sheave passes to one side of the curved track 7 of the by-pass member into the position shown in Figure 6. The turning movement 70 of the scraper is continued until the guide sheave is passed and the tail rope 5 is engaged thereby, as shown in Figure 7. During the turning movement just described the scraper is filled with loose material but the 75 forward end of the slot 11 through which the sheave 12 and supporting arm 15 are passed is maintained free of loose material by means of a shield 20. In the preferred form shown it will be observed that the 80 rearward end of the by-pass track 7 approaches the rearward end of the scraper quite closely. I find this form to be desirable in order to provide a compact construction wherein the by-pass connection and tail 85 rope are kept close to the walls of the scraper so as to facilitate the loading operation. In this instance it is necessary to elongate the slot 11 through which the guide sheave 12 and its supporting arm 15 extend 90 so that a portion of said sheave and arm pass through and within the boundaries of the scraper while passing this point. I have determined by experiment that under ordinary 95 conditions the loose material forms no serious obstruction to the continuous movement of the guide sheave at this point. It is manifest however that the by-pass member may be spaced at a greater distance from the scraper, especially at the rear end thereof so that the guide sheave 12 and its support may pass clear of the outer surface of the scraper thus eliminating all possibility 100 of obstruction at this point.

Although I have shown and described one 105 form in which my invention may be embodied it will be understood that the construction and arrangement of the various parts may be altered without departing from its spirit and scope. I do not therefore, wish to be construed as limiting myself to the specific embodiment illustrated and described, excepting as it may be limited in the appended claims.

110 I claim as my invention:

1. In a scraper loading apparatus, a scraper, a by-pass member connected to said scraper, draft ropes connected to said by-pass member and forming therewith a continuous bearing surface for a fixed guide whereby the scraper is turned while in engagement with said guide.

2. In a scraper loading apparatus, a scraper, a by-pass member connected to said scraper comprising a track adapted for en-

gagement with a guide, said track extending in offset relation from the front to the rear end of the scraper and having draft ropes attached at the opposite ends thereof to form a continuous bearing surface for said guide.

3. In a scraper loading apparatus, a scraper, a by-pass member connected to said scraper comprising a track adapted for engagement with a guide, said track extending in offset relation from the front to the rear end of the scraper and having draft ropes attached at the opposite ends thereof substantially on the longitudinal axes of said scraper to form a continuous bearing surface for said guide.

4. In a scraper loading apparatus, a scraper provided with side walls, a by-pass member connected to said scraper and adapted to provide continuous bearing for a fixed guide, said by-pass member intersecting one side wall of said scraper and extending rearwardly about the outside thereof, and draft ropes attached at opposite ends of said by-pass member.

5. In a scraper loading apparatus, a scraper having a head and tail line adapted for reciprocably moving the same, a guide adapted to be fixed at a predetermined point for engagement with said draft ropes, and means on said scraper permitting free passage of said guide from one end of the scraper to the other in either direction whereby said draft ropes may be successively engaged and the scraper turned while in engagement with said guide.

6. In a scraper loading apparatus, a scraper provided with side walls, a by-pass member comprising an inwardly facing track adapted for engagement with a fixed guide, a head rope at the forward end of said by-pass member and a tail rope at the rear end thereof, said ropes forming with

said by-pass member a continuous bearing surface for said guide.

7. In a scraper loading apparatus, a scraper provided with side walls, a by-pass member comprising an inwardly facing track adapted for engagement with a fixed guide, and curved laterally in offset relation with the longitudinal axis of the scraper, a head rope at the forward end of said by-pass member and a tail rope at the rear end thereof, said ropes forming with said by-pass member a continuous bearing surface for said guide.

8. In a scraper loading apparatus, a scraper provided with side walls, a by-pass member comprising an inwardly facing track adapted for engagement with a fixed guide, a head rope at the forward end of said by-pass member and a tail rope at the rear end thereof, said ropes forming with said by-pass member a continuous bearing surface for said guide, said by-pass member intersecting one side wall and supported at one side thereof to leave a passageway in said wall for said guide.

9. In a scraper loading apparatus, a scraper provided with side walls, a by-pass member comprising an inwardly facing track adapted for engagement with a fixed guide, a head rope at the forward end of said by-pass member and a tail rope at the rear end thereof, said ropes forming with said by-pass member a continuous bearing surface for said guide, said by-pass member intersecting one side wall and supported at one side thereof to leave a passageway in said wall for said guide, and a shield extending inwardly and over said passageway.

Signed at Chicago, in the county of Cook and State of Illinois, this 25th day of February, A. D. 1924.

CHARLES E. DAVIS.
